US0D1030721S

(12) **United States Design Patent** (10) Patent No.: **US D1,030,721 S**
(45) Date of Patent: ** Jun. 11, 2024

(54) **EARPHONE**

(71) Applicant: **New Audio LLC**, New York, NY (US)

(72) Inventors: **Jonathan Levine**, New York, NY (US); **Thomas C. Wilson**, New York, NY (US); **Marten Wallby**, New York, NY (US); **Zachary Hellman**, New York, NY (US); **Clayton Pipkin**, Highland Park, NJ (US)

(73) Assignee: **New Audio LLC**, New York, NY (US)

(**) Term: **15 Years**

(21) Appl. No.: **29/921,346**

(22) Filed: **Dec. 15, 2023**

Related U.S. Application Data

(62) Division of application No. 29/875,437, filed on May 4, 2023, which is a division of application No. 29/768,126, filed on Jan. 27, 2021, now Pat. No. Des. 989,043.

(57) **CLAIM**

The ornamental design for an earphone, as shown and described.

DESCRIPTION

FIG. 1 is a perspective view of an earphone showing our new design;

FIG. 2 is a bottom perspective view thereof;

FIG. 3 is a side elevational view thereof;

FIG. 4 is an opposite side elevational view thereof;

FIG. 5 is a front elevational view thereof;

FIG. 6 is a back elevational view thereof;

FIG. 7 is a top view thereof; and,

FIG. 8 is a bottom view thereof.

1 Claim, 8 Drawing Sheets
